Primary Examiner — Cynthia Underwood*(74) Attorney, Agent, or Firm* — Reed Smith LLP(57) **CLAIM**

The ornamental design for the multi-cable manager, as shown and described.

DESCRIPTION

FIG. 1 is a top perspective view of the multi-cable manager according to an embodiment of the present invention; FIG. 2 is a first side view thereof; FIG. 3 is a second side view thereof; FIG. 4 is a third side view thereof; FIG. 5 is a top plan view thereof; and, FIG. 6 is a bottom plan view thereof.
The broken lines in the drawings illustrate the portions of the design that form no part of the claim.
